Primary Examiner — Michelle E. Wilson*Assistant Examiner* — Richard E Yenchesky*(74) Attorney, Agent, or Firm* — Vincent Pham(57) **CLAIM**

The ornamental design for a floor pad, as shown and described.

DESCRIPTION

FIG. 1 is an orthogonal view showing the new design for a floor pad.

FIG. 2 is a top view thereof;

FIG. 3 is a bottom view thereof, the abrasive on the bottom of the floor pad being optional; and,

FIG. 4 is a right side profile view thereof; the left side view, front side view and back side view thereof being the same. The broken lines form no part of the claimed design and encloses a surface area that forms no part of the claimed design.
